ENGINE STARTING MECHANISM

Raymond P. Lansing, Montclair, N. J., assignor
to Eclipse Aviation Corporation, East Orange,
N. J., a corporation of New Jersey

Application June 30, 1931, Serial No. 543,004

16 Claims. (Cl. 74—7)

This invention relates to starting mechanisms and more particularly to starters for engines of the internal combustion type.

One of the objects of the invention is to provide, in an engine starter, novel means for establishing driving relationship between the starter and a member of the engine to be started.

A further object is to provide a novel device of the foregoing character, embodying means for automatically energizing the starter driving means in response to a predetermined movement of the engine-engaging member of the starter.

A further object of the invention is to provide a novel starter embodying engagement producing means operative upon the engine-engaging member to cause the latter to move directly forward into engine-engaging position prior to imparting any rotary movement thereto.

A further object of the invention is to provide in a motor-driven starter of the type above described, novel means for delaying the establishment of driving relationship between the motor and the engine-engaging member until the engine-engaging member has completed its engine-engaging movement.

A further object of the invention is to provide in a motor-driven starter of the type above described, novel means for releasing the driving connection between the motor and engine-engaging member independently of any movement of the engine-engaging member away from engine-engaging position.

A further object of the invention is to provide in a motor-driven starter of the type above described, novel means for releasing the driving connection between the motor and engine-engaging member automatically in response to starting of the engine under its own power.

Another object of the invention is to provide apparatus of the foregoing character which embodies a one-way driving connection between the motor and the engine, which one-way driving connection is constituted by novel driving mechanism eliminating the necessity of employing any of the usual overrunning clutch constructions.

Another object of the invention is to provide apparatus of the foregoing character, which is relatively simple in construction, readily accessible, and positive in its operation.

Other objects and advantages to be derived from the use of the invention disclosed herein will become evident on an inspection of the following description when read with reference to the accompanying drawings illustrating three embodiments of the invention. It is to be expressly understood, however, that said drawings are for the

purpose of illustration only and are not to be construed as a definition of the limits of the invention, reference being had for this purpose to the appended claims.

In the drawings,

Fig. 1 is a longitudinal sectional view of a device embodying the invention;

Fig. 2 is a similar view, showing the parts in cranking position;

Fig. 3 is a longitudinal sectional view of a modification;

Fig. 4 is a similar view of the device shown in Fig. 3 but with the parts shown in cranking position;

Fig. 5 is a longitudinal sectional view of another modification;

Fig. 6 is a similar view of the modification shown in Fig. 5, but with the parts in cranking position; and

Fig. 7 is a view of certain of the parts shown in Figs. 5 and 6, showing the action in the event of non-alignment of the teeth.

Referring to the drawings, and particularly to Figs. 1 and 2, the invention is therein shown embodied in a device having a prime mover 1, 80 herein shown in the form of an electric motor whose armature shaft 2, extended as indicated at 3, constitutes the driving shaft of the starting mechanism. A casing or bracket 4 extends from the frame of the motor and at its outer end is 85 provided with a bearing 5 to receive the outer end 3 of the armature shaft. This casing also preferably constitutes the supporting means for a shifting lever 6 which is pivoted to the casing by suitable means as indicated at 7, and which extends 90 into the casing in the form of a yoke with its lower ends 8 in a position to engage a pair of flanges 9 and 9a constituting parts of the shifting means hereinafter described.

The lever 6 is provided preferably with an annular projection 10, which, in its travel in a clockwise direction, is adapted to contact and operate the button 11 of a switch of proper construction to supply the motor 1 with current and control the energization and de-energization thereof.

The lever 6 is adapted to be manually operated by the operator through suitable linkage or operating connections which are of the usual character and therefore not necessary to be shown in further detail. The term "manual" as used herein is intended to embrace operation by foot or pedal as well as by hand, the term being employed in its broadest sense to indicate any action controlled arbitrarily rather than automatically.

The novel means for drivably connecting the

armature shaft 2 with the engine, a rotatable member of which is indicated at 14, is herein shown as constituted by an assembly of parts adapted to coact with suitable formations on the 5 shaft 2, such as the screw threads 15. In the embodiment shown in Figs. 1 and 2, these threads 15 are cut into the shaft and the shoulder 40 thus formed serves to limit the longitudinal movement of the correspondingly threaded nut or 10 clutch member 16 which surrounds the shaft 2 at the threaded portion and which is preferably provided with laterally projecting teeth or jaws 17 adapted to register at the proper time and in the proper sequence with corresponding lateral 15 projections 18 on a cooperating clutch member or collar 19. The collar 19 is splined or otherwise secured to a drum or barrel member 20 for rotation in unison therewith. The member 20 is preferably in the form of a hollow cylinder with 20 an inwardly turned edge or flange 21 at its forward end, the said flange 21 having splines or other suitable means for connection with the engine-engaging member 22, the latter being here shown in the form of a pinion adapted to register 25 with the teeth 23 formed on the rotatable engine member 14. This engine member is preferably of a considerably larger diameter than the diameter of the pinion 22, and in practice will be fixed to a flywheel or similar member drivably connected to the engine crankshaft.

The novel means for normally maintaining the members 16 and 19 in the positions indicated in Fig. 1 further include a second nut 27 threadedly secured to the shaft 2 by threads of much 35 smaller size than threads 15, and of a pitch such as to preclude possibility of longitudinal movement of the nut 27 along the shaft 2. Interposed between the nut 27 and the flange 21 of the barrel 20 is a washer 28 rigid with pinion 22 and serving as a seat for a compression spring 29, the opposite end of which bears against the surface of the member 19, the latter being held against rearward movement by engagement with the shoulder 31 on the shaft 2.

45 The means for shifting pinion 22 into engagement with the engine member 14 comprises, in addition to the lever 6 and flanges 9 and 9a with which the lever registers, a cylindrical member or sleeve 32 on which the flanges 9 and 9a are 50 formed, the said sleeve surrounding the barrel 20 and terminating in inwardly turned fingers 33 against which clutch member 19 is constantly urged by the stress in the compression spring 29, the said fingers 33 being disposed within longitudinal slots or splines 34 formed in the barrel 20, such construction permitting axial movement of the clutch member 19 relatively to the barrel 20, while at the same time insuring unitary rotary movement of all three parts. In order to prevent relative longitudinal movement of the sleeve 32 and barrel 20, the barrel 20 is provided with apertures 35 adapted to receive projections 36 formed at corresponding radial positions on a retaining ring 37 fitting the inner cylindrical surface of the barrel 20.

In operation, the turning of the lever 6 about its support 7 first produces a longitudinal thrust 70 on the sleeve 32, which thrust is transferred to the pinion 22 through the fingers 33, clutch member 19, spring 29, and annular member 28. This axial thrust causes the pinion 22 to move forward into meshing engagement with the engine member 14. As soon as engagement is effected, the continued clockwise motion of the lever 6 75 presses projection 10 against button 11 with suffi-

cient pressure to close the switch to start the motor. Thereupon the resulting rotation of shaft 2, in conjunction with the inertia of the nut 16, causes the latter to move rearwardly along the threads 15, thereby bringing the teeth 17 thereof into driving engagement with the teeth 18 on the clutch member 19, as shown in Fig. 2. This establishes a drive from the motor shaft 2 through clutch members 16 and 19, barrel 20 and pinion 22 to the engine member 14.

The engine is, by the means just described, turned over sufficiently to cause starting thereof under its own power, on the occurrence of which the resulting sudden acceleration of the pinion 22, barrel 20 and clutch members 19 and 16, all of which remain drivably connected, causes a reverse screw action between the members 16 and shaft 2, thereby moving the member 16 from the position shown in Fig. 2 to the normal position indicated in Fig. 1. Such movement separates the driving surfaces 17 and 18 and thereby prevents reverse drive of the motor shaft 2 from the engine member 14. Accordingly, excessive speed cannot be developed in the motor even though the operator is dilatory in returning the 100 lever 6 to the normal position. On such return, the switch 11 of course resumes its normal position, thereby de-energizing the motor, and the pinion is released from engagement with the engine member 14.

In the event that the teeth of pinion 22 strike those of the engine member 14 during the forward meshing movement of the former, the resulting compression of spring 29 against its seat on annular member 28, will permit completion of 110 the shifting movement of lever 6 and consequently will permit closure of the circuit to the motor. The resultant rotation of the shaft 2 will first engage jaws 16 and 19 and will then cause sufficient rotary movement of the pinion to bring its 115 teeth into registry with the spaces between the teeth of member 14, whereupon the previously compressed spring 29 will become effective to snap the pinion into full meshing engagement with the flywheel member and thus establish crank- 120 ing relation therebetween.

In the embodiment shown in Figs. 3 and 4, the operation is substantially the same but the structure is somewhat different in that the motor shaft 2' is provided with a thread 15' of opposite 125 pitch so that the nut 16', which corresponds in function and method of operation to the clutch member 16 of Fig. 1, moves in an opposite direction. In this modification the nut 27' acts as a stop for the clutch member 16', the member 35' 130 limiting its rearward movement. This embodiment also utilizes the principle of automatic release of driving relation between the motor and the engine, immediately upon the starting of the latter under its own power, and even though the 135 engine-engaging member is still in mesh with the enlarged member of the engine.

It will be further noted that in both embodiments above described, the invention provides means for producing engagement between the 140 starter and the engine prior to energization of the driving means, together with means for drivably disconnecting the starter prior to physical release of the engine-engaging parts and without the necessity of employing any of the usual types 145 of overrunning clutch. Moreover, both said embodiments include means for transmitting the driving torque to the engine-engaging member at points spaced from the motor shaft (that is, the teeth of the pinion rather than its shaft con- 150

- tacting surface), thereby making it feasible to employ a smaller pinion that would otherwise be necessary and without sacrificing mechanical strength, to guard against the possibility that, due to vibration of the parts or for any other reason, the clutch member 16 of the modification shown in Figs. 1 and 2 should travel rearwardly on shaft 2 during engine operation so as to be in the rearward position at the initiation of the next starting operation, thereby interfering with complete oscillatory movement of the shifting and switch closing lever, a suitable friction device, such as a spring pressed plunger, may be mounted on said clutch member to normally press yieldably upon the surface of the shaft and thereby prevent any such rearward movement during the running of the engine. A novel method of overcoming this tendency, if it should occur, is illustrated in the embodiment shown in Figs. 5 to 7 inclusive, wherein movement of the shifting and switch closing lever 50 is transmitted to the barrel member 51 through a coiled spring 52 interposed between the flange 53 on the barrel 51 and the collar 54 surrounding the barrel 51 and in this embodiment, movable along said barrel independently of the associated flange 53. With this construction it is apparent that under normal conditions actuation of the shift lever 50 will first move the pinion 57 from the position indicated in Fig. 5 to the meshing position indicated in Fig. 6 through action of collar 54, spring 52, barrel 51, clutch member 58, and spring 62. Thereupon the closure of the switch 59 and the resultant rotation of the motor shaft 60 will cause clutch member 61 to move into operative engagement with the clutch member 58, the latter having been moved to the position indicated in Fig. 6 from the position indicated in Fig. 5 by the first stage of movement of the lever 50.
- From the foregoing it is apparent that under normal conditions the operation is substantially the same as that in the embodiment shown in Figs. 1 and 2. In the event, however, that the clutch member 61 happens to be already in a rearward position prior to initiation of the actuation of shift lever 50, thereby interfering with the complete movement of the clutch member 58, such interference will not prevent the completion of the switch operating movement of the lever 50, since the collar 54 is still free to move to the left to the position indicated in Fig. 7, compressing springs 52 and causing a closure of the switch 59. The resulting rotation of the parts 60 and 61 will bring the jaws of the latter into registry with those of the clutch member 58, whereupon the spring 52 will be effective to snap the member 58 into full meshing engagement with the complementary clutch member 61. The engine will then be started by transmission of torque to member 23 by way of spring 62 and pinion 57, as in the form shown in Figs. 1 and 2.
- Although only three embodiments of the invention are shown in the drawings, it is to be expected that those skilled in the art may modify the structure and arrangement of the component parts and, therefore, the claims are not to be construed as applicable only to the embodiments herein shown. Thus, for example, the claims are intended to include as a substitute for the direct driving means herein shown, any suitable driving connection interposed between the prime mover and the engine-engaging member. Moreover, if desired, the invention may be embodied in a starter of the inertia type or of the manually operable type, either with or without an inertia member.
- It is to be understood that various other changes may be made in the construction, arrangement and inter-relation of the parts constituting the invention without departing from the spirit thereof, the extent of the permissible variations being ascertainable by reference to the appended claims.
- What is claimed is:
1. In an engine starting mechanism of the type employing a motor-driven engine-engaging member movable into engagement with a member of the engine to be started, the combination with said engine member and engine-engaging member of an electric motor disposed in alignment with said engine-engaging member, a driving connection between said motor and engine-engaging member comprising a pair of toothed members, one of which is mounted for rotary movement with said motor and longitudinal movement into driving relation to said other toothed member, means for causing a reverse longitudinal movement of said first toothed member when the engine starts under its own power, notwithstanding continued engagement between said engine-engaging member and said engine member, and means for withdrawing said engine engaging member from engine engaging position, said means being effective following de-energization of said motor. 80
  2. In an engine starting mechanism of the type employing a driving shaft rotatably supporting an engine-engaging member, the combination with said driving shaft and engine-engaging member of a pair of normally disengaged clutch members between said shaft and engine-engaging member, means operable automatically in response to rotation of said driving shaft for engaging said clutch members to rotate said engine-engaging member, manually operable means for controlling engagement and disengagement of said engine-engaging member, and resilient means interposed between said driving connection and said engine-engaging member to insure completion of the engine-engaging movement irrespective of the resistance encountered during such movement. 90
  3. In an engine starting mechanism, a driven member engageable with the engine to be started and rotatable with said engine after starting thereof, power means, a driving shaft actuated by said power means, a driving connection between said shaft and driven member comprising a toothed member threaded on said shaft for rotary movement therewith and limited longitudinal movement thereon, said member being movable toward said driven member to establish a driving connection between said shaft and driven member, and means for moving said driven member to a non-rotating position following de-energization of said power means. 100
  4. In an engine starting mechanism, a driven member engageable with the engine to be started and rotatable with said engine after starting thereof, power means, a driving shaft actuated by said power means, a driving connection between said shaft and driven member comprising a toothed member threaded on said shaft for rotary movement therewith and limited longitudinal movement thereon, said member being movable away from said driven member on rotation of said driving shaft, a second toothed member surrounding said driving shaft and engageable by said first-named toothed member, and 110
  5. In an engine starting mechanism, a driven member engageable with the engine to be started and rotatable with said engine after starting thereof, power means, a driving shaft actuated by said power means, a driving connection between said shaft and driven member comprising a toothed member threaded on said shaft for rotary movement therewith and limited longitudinal movement thereon, said member being movable toward said driven member on rotation of said driving shaft, a second toothed member surrounding said driving shaft and engageable by said first-named toothed member, and 120
  6. In an engine starting mechanism, a driven member engageable with the engine to be started and rotatable with said engine after starting thereof, power means, a driving shaft actuated by said power means, a driving connection between said shaft and driven member comprising a toothed member threaded on said shaft for rotary movement therewith and limited longitudinal movement thereon, said member being movable toward said driven member on rotation of said driving shaft, a second toothed member surrounding said driving shaft and engageable by said first-named toothed member, and 130
  7. In an engine starting mechanism, a driven member engageable with the engine to be started and rotatable with said engine after starting thereof, power means, a driving shaft actuated by said power means, a driving connection between said shaft and driven member comprising a toothed member threaded on said shaft for rotary movement therewith and limited longitudinal movement thereon, said member being movable away from said driven member on rotation of said driving shaft, a second toothed member surrounding said driving shaft and engageable by said first-named toothed member, and 140
  8. In an engine starting mechanism, a driven member engageable with the engine to be started and rotatable with said engine after starting thereof, power means, a driving shaft actuated by said power means, a driving connection between said shaft and driven member comprising a toothed member threaded on said shaft for rotary movement therewith and limited longitudinal movement thereon, said member being movable toward said driven member on rotation of said driving shaft, a second toothed member surrounding said driving shaft and engageable by said first-named toothed member, and 150

means drivably connecting said second-named toothed member with said driven member to establish a driving connection between said shaft and driven member, when said toothed members engage.

5. In an engine starting mechanism, a pinion engageable with the engine to be started and rotatable with said engine after starting thereof, power means, a driving shaft actuated by said power means, a one-way driving connection between said shaft and pinion comprising a toothed member threaded on said shaft for rotary movement therewith and limited longitudinal movement thereon, said member being movable away from said pinion on rotation of said driving shaft, a second toothed member surrounding said driving shaft and engageable by said first-named toothed member, and means interlocked with both said second-named toothed member and said driven member to establish a driving connection between said shaft and pinion.

6. In an engine starting mechanism of the type employing a driving shaft rotatably supporting an engine-engaging member, the combination with said driving shaft and engine-engaging member of a pair of normally disengaged clutch members between said shaft and engine-engaging member, means operable automatically in response to rotation of said driving shaft for engaging said clutch members to rotate said engine-engaging member, manually operable means for controlling engagement and disengagement of said engine-engaging member, and resilient means interposed between said driving connection and said engine-engaging member to insure completion of the engine-engaging movement irrespective of resistance encountered due to premature engagement of said clutch members.

7. In an engine starting mechanism of the type employing a driving shaft rotatably supporting an engine-engaging member, the combination with said driving shaft and engine-engaging member of a pair of normally disengaged clutch members between said shaft and engine-engaging member comprising a member threaded to said shaft for rotary movement therewith and longitudinal movement thereon, means operable automatically in response to rotation of said driving shaft for engaging said clutch members to rotate said engine-engaging member, means for rendering said meshing connection ineffective when the engine becomes self-operating, even though said engine-engaging member remains connected to said engine, and manually operable means for controlling engagement and disengagement of said engine-engaging member.

8. In an engine starting mechanism of the type employing a driving shaft rotatably supporting an engine-engaging member, the combination with said driving shaft and engine-engaging member of a pair of normally disengaged clutch members between said shaft and engine-engaging member, comprising a clutch jaw threaded to said shaft for rotary movement therewith and longitudinal movement thereon, means operable automatically in response to rotation of said driving shaft for engaging said clutch members to rotate said engine-engaging member, means for rendering said driving connection ineffective when the engine becomes self-operating, even though said engine-engaging member remains connected to said engine, and common control means for producing axial movement of said engine-engaging member and rotary movement of said driving shaft.

9. In an engine starting mechanism, the combination with a driving shaft and engine-engaging member of a pair of normally disengaged clutch members between said shaft and engine-engaging member, means operable automatically in response to rotation of said driving shaft for engaging said clutch members to rotate said engine-engaging member, and resilient means interposed between said clutch members and said engine-engaging member to insure completion of the engine-engaging movement irrespective of the resistance encountered during such movement, said resilient means including a pair of springs one of which is operative in response to obstruction between the engine-engaging member and the member of the engine engaged therby, and the other of which is operative in response to premature engagement of said clutch members.

10. In an engine starting mechanism, the combination with a driving shaft and engine-engaging member of a pair of normally disengaged clutch members between said shaft and engine-engaging member, means operable automatically in response to rotation of said driving shaft for engaging said clutch members to rotate said engine-engaging member, manually operable means for controlling engagement and disengagement of said engine-engaging member, and resilient means interposed between said driving connection and said engine-engaging member to insure completion of the engine-engaging movement irrespective of resistance encountered due to premature engagement of said clutch members, said resilient means being yieldable to permit relative movement between said manually operable means and the one of said clutch members which normally moves therewith.

11. In an engine starter, in combination, a motor, an engine-engaging pinion having a barrel connected thereto, a screw member driven by said motor, said screw member having an unthreaded portion on which said pinion is mounted, a normally disengaged clutch mechanism one element of which is movable with said barrel to drivably connect said motor and pinion, and the other element of which is threaded on said screw member for axial motion into mesh with said first named clutch element when the motor rotates said screw member, a lever for closing the circuit to said motor and at the same time shifting said clutch member toward the engaged position, and a lost-motion connection between said lever and barrel, said lost-motion connection including a lever operated collar slidably axially of said barrel and a compressible spring operative to transmit thrust from said collar to said barrel.

12. In an engine starter, in combination, a motor, an engine-engaging pinion having a barrel connected thereto, a normally disengaged clutch mechanism, one element of which is movable with said barrel to drivably connect said motor and pinion, and the other element of which is movable axially into mesh with said first named clutch element when said motor is energized, a lever for energizing to said motor and at the same time shifting said clutch member toward the engaged position, and a lost-motion connection between said lever and barrel, said lost-motion connection including a lever operated collar slidably axially of said barrel and a compressible spring operative to transmit thrust from said collar to said barrel.

13. In an engine starter, in combination, a motor, an engine-engaging pinion, a barrel having a slotted portion connected to said pinion, a nor-

- 5 mally disengaged clutch mechanism, one element of which is movable with said barrel to drivably connect said motor and pinion, and the other element of which is movable axially into mesh with
5 said first named clutch element when said motor is energized, a lever for energizing said motor and at the same time shifting said clutch member toward the engaged position, and a lost-motion connection between said lever and bar-
10 rel, said lost-motion connection including a lever operated collar slidable along the slotted portion of said barrel, and a compressible spring operative to transmit thrust from said collar to said barrel.
- 15 14. In an engine starter, in combination, a motor, an engine-engaging pinion having a barrel connected thereto, a normally disengaged clutch mechanism, one element of which is movable with said barrel to drivably connect said
20 motor and pinion, and the other element of which is movable axially into mesh with said first named clutch element when said motor is energized, a lever for energizing said motor and at the same time shifting said clutch member toward the en-
25 gaged position, a lost-motion connection between said lever and barrel including a lever operated collar slidable axially of said barrel, a compressible spring operative to transmit thrust from said collar to said barrel, and a second spring inter-
30 posed between said clutch and said pinion to insure completion of the meshing movement of said pinion irrespective of a temporary condition of non-registry between the meshing surfaces of the pinion and the engine member engaged there-
35 by.
- 36 15. In an engine starter, in combination, a motor, an engine-engaging pinion, a barrel hav-
37 ing a slotted portion connected to said pinion, a normally disengaged clutch mechanism, one ele-
38 ment of which is movable with said barrel to drivably connect said motor and pinion, and the other element of which is movable axially into mesh with said first named clutch element when said motor is energized, a lever for energizing said motor and at the same time shifting said clutch member toward the engaged position, a lost-
39 motion connection between said lever and barrel, said lost-motion connection including a lever op-
40 erated collar slidable along the slotted portion of said barrel, a compressible spring operative to transmit thrust from said collar to said barrel, and a second spring interposed between said clutch and said pinion to insure completion of the meshing movement of said pinion.
- 45 16. In an engine starting mechanism, a driven member engageable with the engine to be started and rotatable with said engine after starting thereof, power means, a driving shaft actuated by said power means, a driving connection between said shaft and driven member comprising a toothed member threaded on said shaft for ro-
50 tary movement therewith and limited longitudinal movement thereon, said member being movable away from said driven member to establish a driving connection between said shaft and driven member, manually operable means for energizing said power means, a second toothed member nor-
55 mally movable with said manually operable means, and resilient means yieldable to permit energization of said power means even though movement of said second named toothed mem-
60 ber with said manually operable means is tem-
65 porarily prevented.
